UNITED STATES PATENT OFFICE.

JOSEPH W. SNELL, JR., OF BAY PORT, MICHIGAN.

STOOL OR CHAIR.

SPECIFICATION forming part of Letters Patent No. 595,352, dated December 14, 1897.

Application filed March 24, 1897. Serial No. 629,076. (No model.)

To all whom it may concern:

Be it known that I, JOSEPH W. SNELL, Jr., a citizen of the United States, residing at Bay Port, in the county of Huron and State of Michigan, have invented certain new and useful Improvements in Stools or Chairs; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to improvements in raising and lowering seats of stools or chairs, and has for its object to provide a device of this character which combines the advantages of simplicity of design and cheapness of construction, thus rendering the same capable of more easy and quick assembling and adjustment of parts and at the same time increasing its efficiency and ease of operation.

To this end my invention consists in the construction and arrangement of parts, as shown in the accompanying drawings and set forth in the following specification.

In the said drawings, Figure 1 is a sectional elevation of my device. Fig. 2 is a horizontal section taken on the line 2 2, Fig. 1. Fig. 3 is a similar view taken on the line 3 3, Fig. 1; and Fig. 4 is a similar view taken on the line 4 4, Fig. 1.

Of the parts represented in the figures, A 35 denotes a standard, which may be either round or rectangular in cross-section. It is provided at its top end with an enlargement C, at its inner edge with ratchets a, and near its upper end with bent arm b. Pivoted connected to top of standard A is seat B. Extending parallel to main standard A is lever-rod D. This is a small rod pivoted at its lower end to standard A and at its upper end to finger-lever d, passing through and being held in 45 position by passing through perforation f in arm b. Passing through the two perforations in arm b is finger-lever d, provided at its outer end with finger-rest h and pivoted at its inner end to rod D. Between the two outer 50 perforations of arm b and encircling the finger-lever is a spring e, the outer edge of said spring resting against outer end of arm b and

attached at its inner end to finger-lever d. (See Fig. 2.) Fitting into base J is the guide H, provided with a central perforation, through 55 which the standard A passes and is held in position. At one side of the central perforation is a perforation M, allowing rod D to pass freely through the same, space being allowed for lateral motion. The upper edge of 60 the main guide projects to form a shoulder which rests on top of the outer edge of base J, forming a means of fastening the guide to base. On the guide H at each side of perforation M are the grooves k. Sliding freely in 65 grooves k is detent j, provided with perforation D', through which rod D passes. (See Figs. 3 and 4.)

Having now indicated the various elements composing my device and the manner in 70 which they are connected, the mode of operation is as follows: Spring e is so arranged that when finger-lever d is pressed in rod D, being pivoted to said finger-lever, is also pressed firmly in toward standard. This 75 keeps the sliding detent j, through which rod D passes, inserted in notches a of standard A. To raise or lower the seat of stool or chair, press out on finger-rest h. This will throw rod D away from standard A, sliding detent j 80 back from the teeth of the standard. The stool may then be raised to any desired point up to the place where the under-bent arm of rod D hits partition J' of the guide H. (See Fig. 1.) When the stool is raised to the de- 85 sired point and pressure is released from the finger-rest h, the spring e will then firmly press rod D in toward the standard A, forcing sliding detent j in ratchets a of said standard. The seat B is pivoted and will revolve 90 without touching or changing location of the finger-lever. With the above construction it is not necessary for the operator to leave the stool in adjusting the same.

It is understood that this invention is not 95 limited to the precise form and mode of arranging parts shown in the drawings, but that minor variations may be made therein, provided there is no departure from the main scope of the invention.

Moreover, while I have described my invention as more particularly designed to be applied to stools or chairs it will be understood that it may be used in connection with

analogous articles of furniture—such, for instance, as tables, lamp-stands, and the like.

Having thus described my invention, what I claim is—

- 5 1. The combination with a supporting-base, and a serrated standard vertically movable therein and supporting a top such as a stool or chair seat, of a vertical rod pivoted at its lower end to said standard, a horizontally-
10 movable pull-lever engaged with the upper end of said rod, means for normally retaining said rod in proximity to said standard, and a detent sliding in guides in said base and controlled in its movement by said rod for engaging with the serrations in said standard 15 and to retain the same in any adjusted position, substantially as described.
2. The combination with a supporting-base, a serrated standard vertically movable there-
20 in and supporting a top such as a stool or chair

seat, and a horizontal arm or bracket supported by said standard near its upper end, of a vertical rod pivoted at its lower end to said standard, a pull-lever movable in said arm or bracket and pivoted to the upper end of said vertical rod, a spring engaged with said pull-lever for normally retaining said vertical rod in proximity to said serrated standard, and a detent sliding in guides in said base and controlled in its movement by said vertical rod 25 for engaging with the serrations in said standard to retain the same in any adjusted position, substantially as described.

In testimony whereof I have hereunto set my hand in the presence of two subscribing 30 witnesses.

JOSEPH W. SNELL, JR.
